Primary Examiner — Martie K Holtje(74) *Attorney, Agent, or Firm* — Peter L. Brewer; David F. Sawrie; Baker Donelson(57) **CLAIM**

We claim the ornamental design for a handheld transmitter, as shown and described.

DESCRIPTION

This application is related to co-pending U.S. Ser. No. 29/479,170, filed Jan. 13, 2014.

FIG. 1 is a top, right front perspective view of a handheld transmitter showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is left side elevational view of thereof; and,

FIG. 8 is a bottom, left front perspective view thereof.

The structural features depicted by broken lines have been shown for the purpose of illustrating portions of the handheld transmitter that form no part of the claimed design.
